[57] **CLAIM**

The ornamental design for pair of eyeglass temples, as shown and described.

DESCRIPTION

FIG. 1 is a top plan view of a pair of eyeglass temples showing my new design;

FIG. 2 is a front elevational view thereof;

FIG. 3 is a right side view thereof; and,

FIG. 4 is a top plan view of the temple spring, shown separately for ease of illustration only.

The broken line showing of the eyeglass frame in FIGS. 1-3 is for ease of illustration only and forms no part of the claimed design.
